United States Patent [19]

Wilder

[11] Patent Number: Des. 310,868

[45] Date of Patent: ** Sep. 25, 1990

[54] WELD FLANGE

[76] Inventor: Don R. Wilder, 1881 N. Ukiah Way,
Upland, Calif. 91783

[**] Term: 14 Years

[21] Appl. No.: 52,742

[22] Filed: May 21, 1987

[52] U.S. Cl. D23/265

[58] Field of Search 285/416, 405, 412, 363,
285/365, 358, 286; D23/259, 262, 265

[57] CLAIM

The ornamental design for a weld flange, as shown and described.

DESCRIPTION

FIG. 1 is an isometric view of a weld flange showing my new design;

FIG. 2 is a top plan view thereof;

FIG. 3 is a cross-sectional view taken on line 3—3 of FIG. 2; and

FIG. 4 is a bottom plan view thereof.

U.S. Patent
